ANCHORING MEMBER FOR SHEET PILINGS

Enno Becker, Bremen, Germany

Application February 8, 1932, Serial No. 591,730
In Germany February 10, 1931

7 Claims. (Cl. 61—49)

The known anchoring of the irons of sheet pilings has sometimes the disadvantage that particularly in such constructions where the soil behind the sheet-piling is subsequently filled up, the anchoring members which hold the girder rearwardly are strained in a disadvantageous manner due to the setting up of the filling. In order to remove this inconvenience it has indeed been attempted to provide joints inwardly of the anchor, but it has not succeeded in transmitting the stresses of the anchor in such a way as to strain advantageously the anchor. Moreover it is very often requested to pass about existing obstacles without shifting the regular distribution for the points of application of the anchor in the girder.

According to the invention the disadvantageous stresses of the anchor are avoided by providing a joint in the girder, this joint allowing a reliable turning of the anchor in the perpendicular plane of the same. In order to pass about existing obstacles the joint is formed as a cross-joint so that the anchor is pivotally movable in all directions.

The annexed drawing shows, by way of example, a form of embodiment of the invention.

In this drawing,

Fig. 1 is a schematic view of the anchoring device,

Fig. 2 is a partial section and side view according to Fig. 1 on a larger scale, and

Fig. 3 is a plan view of the arrangement shown in Fig. 2.

In these figures, the connecting-piece *f* is movably attached by means of a screw-bolt *e* to a joint-piece *c*, this latter being by another bolt or pivot *d* which lies perpendicular to the bolt *e* pivotally mounted between two U-shaped irons *a*. Either of these U-irons are attached to the sheet-piling in a known way.

The pivotal axes of the cross-joint piece which are disposed perpendicularly to each other may be formed by two bolts which extend through the body of the cross-joint and must be relatively disposed by at least the sum of their radii in order to pass by each other (see Figs. 2 and 3) or one pivotal axis may be formed by two pins protruding from the body of the cross-joint while the other axis is constituted by a bolt passing therethrough. In the latter case, the two pivot axes perpendicular to each other need not be relatively disposed but may intersect each other.

Also in the latter case the connecting-piece *f* will be either movably or rigidly attached to the anchor *g*.

What I claim and desire to secure by Letters Patent in the United States is:

1. Anchoring device for sheet-piling, consisting of a girder transversely attached to the sheet-piling, a cross-joint-piece pivotally mounted in the said girder, a connecting-piece pivotally connected to the cross-joint-piece and an anchor movably attached to the connecting-piece, the pivotal axes of the cross-joint-piece and the connecting-piece being perpendicular in relation to one another. 60

2. Anchoring device for sheet-piling, consisting of a girder transversely attached to the sheet-piling, a cross-joint-piece pivotally mounted in the said girder, a connecting-piece pivotally connected to the cross-joint-piece and an anchor movably attached to the connecting-piece, the pivotal axes of the cross-joint-piece and the connecting-piece being perpendicular in relation to one another, while that of the connecting-piece 70 and the anchor are parallel. 75

3. Anchoring device for sheet-piling, consisting of a girder transversely attached to the sheet-piling, a cross-joint piece pivotally mounted in the said girder, a connecting-piece pivotally connected to the cross-joint-piece and an anchor movably attached to the connecting-piece, the said girder consisting of two U-irons attached with their one flange to the irons of the sheet-piling and enclosing between them the cross-joint-pieces of the single anchors. 80 85

4. Anchoring device for sheet-piling, consisting of a girder transversely attached to the sheet-piling, a cross-joint-piece pivotally mounted in the said girder, a connecting-piece pivotally connected to the cross-joint-piece and an anchor movably attached to the connecting-piece, the said girder consisting of two U-irons attached with their one flange to the irons of the sheet-piling and enclosing between them the cross-joint-pieces of the single anchors, positioned at the girder in desired spaces from one another and independent on the spaces of the irons of the sheet-piling. 90 95

5. Anchoring device for sheet-pilings, consisting of a girder attached to the sheet-piling, a cross-joint-piece pivotally mounted in the said girder and an anchor pivotally connected to the cross-joint-piece, the pivotal axes of the cross-joint-piece and of the anchor being perpendicular in relation to one another. 100 105

6. Anchoring device for sheet-pilings, consisting of a girder attached to the sheet-piling, a cross-joint-piece pivotally mounted in the said girder, a connecting-piece pivotally connected to the 110

the cross-joint-piece and an anchor attached to the connecting-piece, the pivotal axes of the cross-joint-piece and of the connecting-piece being perpendicular in relation to one another.

5 7. Anchoring device for sheet-pilings, consisting of a girder transversely attached to the sheet-piling, a cross-joint-piece pivotally mounted in

the said girder, a connecting-piece pivotally connected to the cross-joint-piece and an anchor rigidly connected to the connecting-piece, the pivotal axes of the cross-joint-piece and of the connecting-piece being perpendicular with relation 80 to one another.
